AUTOMATIC MACHINE ALIGNING
MECHANISM

Montie M. Hart, Buena Park, Calif.

Application March 19, 1934, Serial No. 716,311

4 Claims. (Cl. 1—14)

My invention relates to box making machines, and more particularly to those of the type used in the produce industry, a main object of my invention being to correct certain deleterious effects caused by the operation of machines heretofore proposed, my invention, of course, being in no way limited to said type of machines.

In the type of box making machines heretofore proposed for the produce industry serious difficulty has been encountered in properly centering the box head holding devices or mechanism so that the slats may be accurately positioned on said heads, prior to nailing, it being a common occurrence that when the box has been completed the slats thereof are improperly placed in a slip-shod manner, or certain of said slats, when nailed to said heads overlap the box or are even omitted, resulting in defective boxes. This feature is accentuated by reason of the weight placed upon the heads of the boxes as well as the impact when the slats are nailed thereto. Further, due to wear, caused by the operation of the machines heretofore proposed, certain parts get out of alignment, or even when said machines are placed on the market said parts are already out of alignment, thus causing trouble at the outset, and resulting in imperfect and frequently unusable boxes, thereby also producing unnecessary delays in production. By the use of my invention all these deleterious effects are effectively overcome.

It accordingly is an object of my invention to provide a novel form of mechanism or apparatus for continuously holding in alignment the box head holding disks of a box making machine, whereby the slats of said boxes may be accurately positioned on said heads and nailed irrespective of wear conditions, or inaccurate workmanship inherent in the machines as they are placed on the market, said machine or apparatus comprising means associated with the slideable or shifting arms of the machine, which arms have mounted thereon the box head holding disks, which means may either be integral with said arms or detachably associated therewith, and may comprise a base member with which is suitably associated an arm, which may have on its end an anti-friction device, such as a suitable roller adapted to engage and coact with a stationary part of the framework of the machine so that said arms will at all times during the operation of the machine hold said disks and the box heads in direct alignment to the end that an accurate and finished box may at all times be produced.

The above and further objects and advantages of my invention, as will hereinafter more fully appear, I attain by the construction described in the specification and illustrated on the drawing forming a part of my application.

Reference is had to the accompanying drawing, in which similar reference characters denote similar parts. In the drawing,

Fig. 1 is a fragmentary, part sectional and part elevational view of a conventional box making machine, box heads illustrated in position prior to nailing slats thereon; equipped with my invention,

Fig. 2 is a cross-sectional view, taken on the line 2—2, Fig. 1,

Fig. 3 is an end elevational view of Fig. 1, looking in either direction, since said views are identical, and

Fig. 4 is a fragmentary side elevational view of a modified form of my invention.

Describing my invention more in detail, except insofar as said invention enters into the combination therewith, it forms no part of the conventional box making machine shown and described. Hence, only those parts of said machine or mechanism needed to coact with my invention have been illustrated, such illustrations and description being deemed not needed, especially since my invention is clearly applicable to other machines and apparatus where it is essential that accurate centering or alignment of the parts are needed.

The box-making or box-nailing machine, designated generally by the reference numeral 2, comprises a suitable framework 4, having associated therewith the usual stationary shaft 6, mounted in the conventional manner, not shown, since it forms no part of my invention, except as it enters into the combination therewith, and mounted upon said shaft is a set of arms 8 (Figs. 2 and 3, more particularly), each of said arms being provided with strengthening ribs 10 (Fig. 2); and mounted upon the ends of each of said arms are the box head holding disks 12, by the pins 14, which disks may be cut out as at 16 to reduce their weight to a minimum.

In the conventional machine the disks 12 are provided in pairs, as seen in Fig. 1, and the box heads 18, three in number, that is, the end heads and the center head, are positioned between said disks, prior to the nailing operation. Said conventional machine, also, is provided with automatic mechanism for elevating the heads 18 between the disks 12.

This mechanism is partly shown in Fig. 1 and

comprises a pair of relatively movable members 20, between which said box heads are positioned, which members, after the completed box has been discharged from the machine, are spaced apart and the new box heads 18 elevated between the disks 12, by a mechanism not shown, and the description or illustration of which is not deemed needed, since it forms no part of my invention.

The disks 12 are also actuated so they will move toward and away from the box heads 18, so that said heads may be positioned therebetween and this is accomplished by means of the disk operating lever mechanisms 22-24-26, associated with the rods 28, bearing collars 30, so said rods will automatically move the disks 12 toward and away from the box heads 18, so said heads may automatically be positioned therebetween. The mechanism thus briefly described forms no part of my invention, and hence further description and illustration are not deemed needed.

To oppose the action of the disk operating lever mechanism just described, the rods 28, on the opposite sides of said disks—opposite to said lever mechanism—are provided with the resilient means 32, in the shape of a coil spring, collars 34 and 36 being provided, so the tension of said springs may be adjusted by the set screw 38, so the disks 12, when the box heads 18 are positioned therebetween will be held firmly in position so the slats 40 may be nailed thereto, which in the present instance may be automatically by mechanism, not shown, since it forms no part of my invention. It was thought in practice that by adjusting the collars 34 along the rods 28 it would be possible to nail the slats properly to the heads 18, but practice has determined that such is impossible, and hence my invention, which has so far not yet been described.

As seen in Fig. 2, the slat carrier 42 is positioned between the box heads 18 and disks 12, which slats are housed in a hopper 44, said automatic mechanism (not shown) causes the carrier 42 automatically to place the slats 40 over the heads 18 so said slats may be nailed thereto. Said mechanism also, forms no part of my invention.

It will be obvious that if the slats 40 are not positioned properly over the heads 18, imperfect boxes will result. That is, the slats at each end of the box heads 18 may overlap said ends, if said heads are not always in direct alignment, and as the machine continues to be operated, the misplacing of the slats 40 is accentuated, necessitating the shutting down of the machine, until the disks 12 (and heads 18) are placed in proper alignment. My invention resides in the means for placing said disks and heads in alignment, and insuring that they are continuously kept so.

Fig. 3 illustrates part of the mechanism for turning the disks 12 so the box heads 18 may be turned to the left, in said figure so that said heads may be automatically turned to present the straight edge of said heads at the top, so the slats 40 may be nailed thereto, the nailing mechanism, also, not being shown, since it forms no part of my invention.

Each end of the framework 4 has an upstanding part 46, riveted to a base 48, which part is provided with a cam recess 50, adapted to receive successively the rollers 52 on the disks 12, said rollers, prior to entering said cam recess being guided thereto by means of the fingers 54 and 56, the latter forming part of the spring pressed

latch 58, pivoted as at 60 and held to the part 46 by means of the spring 62.

As the disks 12 rotated (in timed relation by the machine) the rollers 52 enter between the fingers 54 and 56 and these are guided into the cam recesses 50 (at each end of the machine) which causes said disks, and the heads 18 to be rotated as previously described so that the next succeeding edge of the box heads may have the slats 40 nailed thereto in sequence. Said structure, also, forms no part of my invention, and hence further illustration and description are not deemed needed.

My invention will now be described. As previously explained, it is vital to the successful operation of the machine, so that perfect boxes will be formed, that the heads 18 of the boxes will at all times of operation be held in direct alignment, and that, irrespective of wear conditions of the machine. To this end it is necessary that the disks 12 be at all times held in such alignment, so that the slats 40 shall be properly nailed to said box heads.

As will be seen in Figs. 1 and 2, the framework 4 of the machine is provided with a ledge 64, and I make use of said ledge in carrying out my invention.

Each of the arms 8 is provided with an arm or extension 66, either integral with said arm or detachable therefrom, as in practice preferred, and said arm may be provided with a bent portion 68, which bent portion may be perforated to receive the bearing pin and nut assembly 70, for the rollers or other anti-friction devices 72, which rollers or devices are adapted to engage and coat with the ledge 64 so that the disks 12 and box heads 18 are continuously held in alignment.

As the arms 8 are slid on the shaft 6, the rollers 72 are in engagement with the ledge 64, the weight and impact of the nailing operation being communicated to the rollers and ledge through the disks 12 and arms 8, thus preventing said disks (and box heads) from getting out of alignment, and even if the active parts of the machine become worn, said alignment is still maintained, since the arms 66 and rollers 72 coat with the ledge 64 to maintain such alignment. And this is true even when the arms 8 when the box heads 18 and disks 12 are turned by the mechanism previously explained, the rollers 72 engaging the ledge 64 so that said disks 12 are continually kept in said alignment, irrespective of all conditions of operation of the machine or wear of the active parts thereof.

Obviously, the slats 40 will at all times be accurately positioned upon the heads 18 by the slat carrier 42, and the weight and impact induced by the nailing operation will be borne by the rollers 72 on the ledge 64.

In Fig. 4, I have illustrated a slight modification in which my invention may be detachably associated with the arms 8, or said invention applied to other machines where it is vital that certain parts thereof be kept continually in alignment.

In said figure my invention may comprise a base member 74', detachably associated with the arm 8 by means of a dowel pin 76' and a bolt 78', or any other preferred means, and associated with said base member in any way in practice preferred, is an arm 66', with which is associated the rollers 72' and the nut and bearing pin assembly 70'. Obviously the rollers or anti-friction devices or means 72' may be associated with the arms 66' in any manner in practice preferred,

and still remain within the province of my invention.

In accordance with the provisions of the patent statutes, I have described the principle of operation of my invention together with the apparatus or devices which I now consider to represent the best embodiment thereof; but I desire to have it understood that the apparatus or devices shown are only illustrative, and that the invention can 10 be carried out by other means and ways.

I claim as my invention:

1. In a box making machine, a plurality of means for holding the heads of a box, means for positioning slats upon the box heads, means for 15 nailing the slats to the box heads, and means for maintaining the box heads in alignment during the nailing process, such means comprising an arm rigidly secured to each of the said box holding means, a trackway extending longitudinally of 20 the machine, and anti-friction members attached to each of the said arms and adapted to contact the trackway, whereby each of the said box holding means is held in alignment with the other box holding means.
2. In a box making machine, a plurality of means for holding the heads of a box, means for positioning slats upon the box heads, means for 25 nailing the slats to the box heads, and means for

maintaining the box heads in alignment during the nailing process, such means comprising an arm rigidly but removably secured to each of the said box holding means, a trackway extending longitudinally of the machine, and anti-friction members attached to each of the said arms and adapted to contact the trackway, whereby each of the said box holding means is held in alignment with the other box holding means. 5

3. In a box making machine, a plurality of 10 means for holding the heads of a box, means for positioning slats upon the box heads, means for nailing the slats to the box heads, and means for maintaining the said box heads in alignment during the nailing process, such means comprising a 15 stationary shaft, a plurality of arms pivoted upon said shaft and pivotally secured to the said box holding means, a member integral with each of said arms and extending at an angle therefrom, and a trackway extending longitudinally of the 20 machine, the said integral members being adapted to contact the trackway, whereby each of the said box holding means is held in alignment with the other box holding means.

4. A device as set forth in claim 3, in which 25 the integral members are rigidly but removably attached to the arms.

MONTIE M. HART.
